(57) **CLAIM**

The ornamental design for an identification tag for containers, as shown and described.

DESCRIPTION

FIG. 1 is a perspective view of an identification tag for containers showing my new design;

FIG. 2 is a front elevational view thereof;

FIG. 3 is a rear elevational view thereof;

FIG. 4 is a top edge view thereof, it being understood that the bottom edge is a mirror image thereof;

FIG. 5 is a side edge view thereof, it being understood that the opposite side is mirror image thereof; and,

FIG. 6 is a perspective view showing the identification tag on a container.

The portions shown in broken lines are for information only and form no part of the claimed design.
